UNITED STATES PATENT OFFICE.

FRIDOLIN SCHIMMEL, OF FARIBAULT, MINNESOTA.

CUTTER HEAD FOR WOODWORKING MACHINES.

Application filed May 31, 1921. Serial No. 473,682.

To all whom it may concern:

Be it known that I, FRIDOLIN SCHIMMEL, a citizen of the United States, residing at Faribault, in the county of Rice and State of Minnesota, have invented certain new and useful Improvements in Cutter Heads for Woodworking Machines, and I do hereby declare the following to be a full, clear, and exact description of the invention, such as will enable others skilled in the art to which it appertains to make and use the same.

My present invention provides an improved cutter head for use in wood-working machines such as planers and shapers, and generally stated, the invention consists of the novel devices and combinations of devices hereinafter described and defined in the claims.

One of the chief objects of this invention is to provide a cutter head, the cutting action of the several knives of which will be continuous or substantially so, thereby producing a very smooth surface free from waves or irregularities. Another object is to provide efficient knives that may be made at small cost and readily applied in spiral arrangement on the cutter head and which, moreover, when applied, may be readily sharpened. These objects and others are accomplished in the cutter head illustrated in the drawings, wherein like characters indicate like parts throughout the several views.

Referring to the drawings:

Fig. 1 is a plan view of the cutter head, some parts being broken away; and

Fig. 2 is a section on the line 2—2 of Fig. 1.

The body of the cutter head 3 is of substantially cylindrical form with spiral channels therein and it may be formed integral with or driven onto a mandrel 4, but the former construction is illustrated in the drawings. The body of said cutter head 3 is formed with spiral clamp channels or grooves 5 that diverge in cross section, leaving intervening spiral ribs 3^a with approximately parallel sides, which parallel sides, of course, have a spiral trend.

As an important feature, the knives 6 are thin tempered steel blades that are normally or naturally flat but are capable of springing and thereby fitting themselves to the slightly spiral sides of the ribs 3^a, when subjected to pressure from wedge-shaped clamping blocks 7. These clamping blocks 7, are so beveled that when they engage the blades

6 at one side at inner and outer points marked 7^a, they will engage the face of the opposite rib 3^a only at one point 7^b, which is at the center of the outer edge of said block. The bearing edges 7^a are preferably cut away so that they bear only near the ends of the block. This gives the block a four-point bearing against the blade at one side and a one-point bearing against the rib 3^a at the opposite side. Otherwise stated, the clamping block can adapt itself to the blade and its bearing 7^a will then find its proper point of bearing on the opposite rib 3^a.

Screws 8, passed through perforations in the blocks 7 and screwed into radial seats in the head 3, serve to detachably clamp the blocks 7 in position as stated. As these blocks are faced at suitable intervals along the blades, they will securely hold the same, cause said blades to be clamped tightly against the spiral surfaces of the ribs 3^a, and to assume the spiral form of the latter.

As is evident, the knife blades in thin normally flat form may be easily made at comparatively small cost, whereas, heavy knives would have to be ground or cut to spiral form and would be relatively very expensive. Moreover, the thin blades are capable of being easily sharpened, either before or after they are applied to the cutter head. They should be ground and sharpened while applied to the cutter head, and for this purpose, I have devised a highly efficient grinding tool, which is made the subject matter of a companion application, filed of even date herewith under Serial Number 473,682.

A cutter head with knives spirally applied as described will have a continuous cutting action, in that one knife will come into action before the knife just ahead of it has gone out of action, and this goes a long way towards insuring a smooth and waveless or otherwise irregular finished surface. Moreover, the knives are given a sort of a drawing action.

The above features, moreover, produce a cutter head that will require less power to operate it than a cutter head wherein the knives come into action intermittently.

In their outer faces, the spiral flanges 3^a are formed immediately adjacent to the cutting edges of the blades 6, with channels 9. These channels 9 are formed with shoulders that extend parallel to the cutting edges of said blades and, hence, also follow spiral courses. These channels are important, first

because they give clearance for the discharge of the cut chips and, second because their shoulders afford guides for a grinding tool, which, as already stated, is made the subject 5 matter of a companion application, heretofore identified.

The statement made herein and in the 10 claims that the cutter head has longitudinal clamp channels and intervening flanges is used in a broad and liberal sense to mean that they extend in a general direction from one end toward the other of the cutter head and regardless of whether or not they are parallel to the axis of the cutter head or 15 whether or not they follow spiral courses on the cylindrical surface of the cutter head. It will be noted that the clamping blocks 7 are longitudinally spaced, with respect to each other, and the ends of the cutter head 20 3 to afford spaces into which may be inserted a suitable tool to engage the lower edges of the knives 6 and raise the same.

The cutter head described is especially 25 adapted and particularly designed for use in connection with planers and other wood-working machines. The thin cutter blades are especially adapted for action on wood surfaces, whereas, for metal working, much heavier and differently designed cutting 30 edges or blades would be required.

What I claim is:

1. A cutter head comprising an approximately cylindrical body with longitudinal clamp channels and intervening flanges, cutter 35 blades clamped against said flanges, and clamps applied in said channels, adjustably connected to said body and operative to clamp said cutter blades in working positions, said clamps having longitudinally spaced contacts engageable with the cutter 40 blades and also having single contacts located between said longitudinally spaced contacts and engageable with the flanges.

2. A cutter head comprising an approximately cylindrical body with longitudinal clamp channels and intervening flanges, cutter blades clamped against said flanges, and clamps applied in said channels, adjustably connected to said body and operative 50 to clamp said cutter blades in working positions, said clamps having longitudinally and radially spaced contacts engageable with the cutter blades and also having single contacts located between said longitudinally 55 and radially spaced contacts and engageable with the flanges.

3. A cutter head comprising an approximately cylindrical body with longitudinal clamp channels and intervening flanges, cutter 60 blades clamped against said flanges, and a plurality of longitudinally spaced clamps applied in said channels, adjustably connected to said body and operative to clamp the cutter blades in working position, 65 said clamps having longitudinally spaced

contacts engageable with the cutter blades and also having single contacts located between said longitudinally spaced contacts and engageable with the flanges.

4. A cutter head comprising an approximately cylindrical body with longitudinal clamp channels and intervening flanges, cutter blades clamped against said flanges, and a plurality of longitudinally spaced clamps applied to said channels, 70 adjustably connected to said body and operative to clamp said cutter blades in working position, said clamps having longitudinally and radially spaced contacts engageable with the cutter blades and also having single contacts located between said longitudinally and radially spaced contacts and engageable with the flanges.

5. A cutter head comprising an approximately cylindrical body with longitudinal spiral clamp channels and intervening spiral flanges, cutter blades clamped against said flanges, and a plurality of longitudinally spaced clamps applied in said channels, 85 adjustably connected to said body and operative to clamp the cutter blades in working position, said clamps having longitudinally spaced contacts engageable with the cutter blades and also having single contacts located between said longitudinally spaced 90 contacts and engageable with the flanges.

6. A cutter head comprising an approximately cylindrical body with longitudinal spiral clamp channels and intervening spiral flanges, cutter blades clamped against said flanges, and a plurality of longitudinally spaced clamps applied to said channels, 100 adjustably connected to said body and operative to clamp said cutter blades in working position, said clamps having longitudinally and radially spaced contacts engageable with the cutter blades and also having single contacts located between said longitudinally spaced 105 contacts and engageable with the flanges.

7. A cutter head comprising an approximately cylindrical body with longitudinal spiral clamp channels and intervening spiral flanges, cutter blades clamped against said flanges, and a plurality of longitudinally spaced clamps applied in said channels, 115 adjustably connected to said body and operative to clamp the cutter blades in working position, said clamps having longitudinally spaced contacts engageable with the cutter blades and also having single contacts located between said longitudinally spaced 120 contacts and engageable with the flanges.

8. A cutter head comprising an approximately cylindrical body with longitudinal 130

- clamp channels and intervening flanges, cutter blades clamped against said flanges, and clamps applied in said channels, adjustably connected to said body and operative to 15 clamp said cutter blades in working position, said clamps having longitudinally spaced contacts engageable with the cutter blades and also having single contacts located between said longitudinally spaced 20 contacts and engageable with the flanges, said clamps terminating short of the ends of said channels to permit the insertion of a tool into the channels for engagement with the cutter blades to lift the same. 25
- 10 9. A cutter head comprising an approximately cylindrical body with longitudinal clamp channels and intervening flanges, cutter blades clamped against said flanges, and clamps applied in said channels, adjustably

In testimony whereof I affix my signature.

FRIDOLIN SCHIMMEL.
